W. N. PEAK.

WALL PAPER.

No. 17,076.

Patented Jan. 25, 1887.

UNITED STATES PATENT OFFICE.

WILLIAM N. PEAK, OF BROOKLYN, NEW YORK.

DESIGN FOR WALL-PAPER.

SPECIFICATION forming part of Design No. 17,076, dated January 25, 1887.

Application filed December 9, 1886. Serial No. 221,141. Term of patent 3½ years.

To all whom it may concern:

Be it known that I, WILLIAM N. PEAK, of Brooklyn, in the county of Kings and State of New York, have invented and produced a new and original Design for Wall-Paper, of which the following is a full, clear, and exact description.

The nature of my design is fully represented in the accompanying photograph, to which reference is made.

The design consists, principally, of a double raised appearance of the figures, the same being outlined by double borders of different shades. The diamond-shaped figure A is outlined from the ground B by two notched or stepped borders, *a b*, of different shades. These borders at the lower right-hand side of the figure are dark, while at the other sides of the figure they are of light colors, so that they give a double raised appearance or effect of the figure from the ground. The two borders *a b* are set in upon the figure to form the outer surrounding stripe, *c*, of the same color as the figure. Within the body of the figure A are shown double-stepped designs or blocks *d*, and double-stepped borders *f*, producing a design within the figure 'A', having double raised borders. Surrounding the figure A are numerous diamond-shaped or block figures, *C*, and above and below appear the triangular

figures D. The figures C D are of the design shown in the accompanying photograph, and are outlined by double-stepped stripes or borders, producing the double raised appearance both within and at the edges of the figures. 35 All of the figures thus outlined give the appearance to the eye of one figure with beveled edges mounted upon a base of the same outline and somewhat larger than the figure, and also having beveled edges. 40

I claim—

1. The design for wall-paper herein shown and described, the same consisting of a figure of a different color from the ground, showing beveled edges and appearing upon a base of 45 the same outline as the figure, somewhat larger than the figure, and having also the appearance of being beveled at the edges.

2. The design for wall-paper herein shown and described, the same consisting of a figure 50 outlined by two light-and-shadow borders, *a b*, having a beveled appearance and surrounded by an outer stripe *c*.

3. The design for wall-paper, substantially as shown in the accompanying photograph.

WILLIAM N. PEAK.
